UNITED STATES PATENT OFFICE.

EDWIN H. GRAVER, OF CLEVELAND, OHIO, ASSIGNOR TO BELLE B. GELLNER, TRUSTEE,
OF CLEVELAND, OHIO.

INCINERATOR DOOR.

Application filed March 11, 1926. Serial No. 93,828.

This invention is concerned with incinerators for the disposal of garbage and has for its object the provision of a charging door for an incinerator furnace embodying operative features which will permit the charging of garbage into the incinerator while preventing the escape of noxious gases therefrom.

Other objects of my invention will be set forth in the following description which pertains to the accompanying drawings. The essential characteristics are summarized in the claims.

In the drawings Fig. 1 is a cross-sectional elevation of an incinerator provided with a charging door embodying the features of my invention; Fig. 2 is an enlarged cross-sectional detail of the door structure and Fig. 3 is a cross-sectional view taken substantially along the line 3—3 of Fig. 2.

My invention contemplates the provision of a charging door for a garbage incinerator of the general type disclosed in my application filed on an even date herewith. It frequently occurs that it is desired to charge garbage into an incinerator while the incinerator is in operation and in modern incinerators such as are installed in apartment houses, hospitals, etc., it is the practice to charge the garbage into the incinerator at an elevation relative to the fire box of the incinerator, whereby the garbage may first be deposited upon a drying shelf or grate where it may be dehydrated or desiccated. Accordingly, the charging doorway is built into the incinerator structure at such elevation that natural gas will not prevent the escape of noxious gases, if such doorway is opened when the incinerator is in operation. I accordingly provide a doorway structure for an incinerator of the character referred to which is provided with an inner door and an outer door and the volumetric capacity of the door structure is such that by maintaining the inner door closed I may deposit a considerable amount of garbage in the doorway or door passage and thereafter close the outer doorway before opening the inner doorway to permit the garbage to be deposited upon the drying grate.

In Fig. 1, I show a charging doorway or passageway in the form of a large tube 10 extending through the floor 12 of a building in which an incinerator 14 is installed. This tube 10 extends also through the top wall

15 of the incinerator structure 14 with its inner end terminating above a drying shelf 16 of the incinerator. The garbage charged through the doorway is deposited upon the drying shelf 16 and after being dried is 60 thereafter moved to a fire grate 18 where it is consumed by combustion.

As shown in Fig. 1, the incinerator structure is provided with a flue 20 through which the steam and burnt gases escape 65 from the incinerator in a well known manner. The lower end of the doorway or tube 10 may be closed by a flat disk-like member 22 and the outer or upper end of the tube may be closed by a flat disk-like 70 member 24, both of which closely fit the end surfaces of the door tube which are preferably formed to be parallel. The closure members 22 and 24 may be mounted upon an offset bar or shaft 30 which is preferably mounted on a branch portion 10^a of the doorway tube 10 whereby the shaft may extend from end to end through the member 10 without permitting the escape of 75 gases from the incinerator.

To permit the door members 22 and 24 to be operated independently, the lower closure member 22 is rigidly secured to the lower end of the bar 30 by a pin 23, while the upper closure member 24 is loosely 80 mounted on the bar and the upper end of the bar is provided with a handle in the form of a turning knob or wheel 25 for swinging the lower or inner door. A resilient means in the form of a spring 26 may 85 be disposed on the shaft intermediate the closure or door member 24 and the handle wheel 25 whereby the closure member 22 and closure member 24 are always urged into 90 intimate contact with the ends of the doorway tube 10 by reaction through the bar. A knob 24^a may be provided on the top closure member 24 whereby it may be shifted to expose the interior of the doorway tube 10 without causing a shifting movement of 95 the bottom closure member 22 and by turning the wheel handle 25, the bottom of the closure member 22 may be shifted to open the bottom of the doorway tube 10, while the top closure member 24 maintains the 100 top end of the tube sealed.

It will thus be seen that I provide a very simple yet efficient door construction for an incinerator which will permit the charging of garbage into the incinerator when the 110

same is in operation, while at the same time preventing the escape of noxious gases therefrom.

I claim:

- 5 1. In an incinerator door structure the combination of a tubular door frame having flat parallel end surfaces, flat members engaging said parallel surfaces to enclose the door frame, means extending through the door frame for operating one of the members and means engaging said last named means for yieldingly urging said members into intimate contact with said parallel surfaces of the door frame.
- 15 2. In an incinerator door structure the combination of a unitary door frame having parallel end surfaces, members engaging said parallel surfaces to enclose the door frame, means connected to the door frame for operating one of the members and means engaging said last named means for urging said members into intimate contact with said parallel surfaces of the door frame.
- 20 3. The combination with an incinerator wall having a garbage feed opening of an integrally cast door frame, an inner clo-

sure member in slidable engagement with an end of the door frame, an outer closure member in slidable engagement with the opposite end of the door frame and a spring 30 for yieldingly urging said closure members into intimate contact with the ends of the door frame.

4. The combination with an incinerator wall having a garbage feed opening, of a 35 door frame disposed in said opening, and projecting on the inner and outer sides of the incinerator wall, an inner closure member and an outer closure member in slid- 40 able engagement with the door frame ends.

5. In a door structure for an incinerator, the combination of a door frame having flat end surfaces, members mounted on the frame slidably engaging said flat end surfaces, and means for independently operat- 45 ing said members including resilient means for urging said members into engagement with the end surfaces of the door frame.

In testimony whereof, I hereunto affix my signature.

EDWIN H. GRAVER.
